(57) CLAIM

The ornamental design for a guitar, as shown and described.

DESCRIPTION

FIG. 1 is a perspective view of the guitar;
FIG. 2 is top plan view thereof;
FIG. 3 is a bottom plan view thereof;
FIG. 4 is a right side elevational view thereof;
FIG. 5 is a left side elevational view thereof;
FIG. 6 is an enlarged rear side elevational thereof; and,
FIG. 7 is an enlarged front side elevational thereof.
The broken lines in the drawings illustrate portions of the guitar and form no part of the claimed design. The dash-dot-dash line defines the bounds of the claim design and forms no part thereof.

1 Claim, 5 Drawing Sheets
